UNITED STATES PATENT OFFICE

ADAM DAGG, OF HOLLYWOOD, ILLINOIS

ROOF JOINING

Application filed December 12, 1929. Serial No. 413,497.

My invention relates to improvements in roof joinings, and particularly to an improved means for making water proof joints between the roof and walls of a building structure.

The objects of my invention are to provide a roof joining structure which is adapted to be manufactured as a unit in a factory, and to be incorporated as a unit in the building wall structure when the latter is being built; to provide a roof joining structure which is simple to use, easily applied, and which is not apt to permit leaks to develop between the roof and wall; to provide a structure which may be handled with great facility during transportation of the same from the factory to the job; and in general, it is the object of my invention to provide an improved roof joining structure of the type referred to.

Other objects and advantages of my invention will be understood by reference to the following specification and accompanying drawings, in which I have illustrated a roof joining structure embodying a selected form of my invention.

In the drawings:

Fig. 1 is a perspective of a preferred form of my improved roof joining.

Fig. 2 is an end view, partly in section and partly in elevation, showing the manner in which my improved roof joining is used.

Fig. 3 is a section on the line 3—3 of Fig. 2, and

Fig. 4 is an end elevation of my improved roof joining showing the manner of bundling the flashing element during shipment of the structure and during the initial stages of its incorporation in a wall structure.

Referring now to the drawings, it will be seen that my improved roof joining consists of a wall member or block 10 and a flashing 11. The flashing 11 may be a single or multiply flashing to suit the requirements of any particular job, and in the present instance, I have shown a two-ply flashing including top and bottom plies 12 and 13 respectively. As clearly shown in Figs. 1 and 2, the top ply 12 extends beyond the bottom ply, this being for the purpose of forming a so-called feather

edge on the completed job, as indicated at 14.

The wall member or block 10 may be formed of a single block, but I prefer to form the same of upper and lower sections 15 and 16 respectively, between which marginal 55 portions such as indicated at 17 of the flashing plies are disposed. The top and bottom sections 15 and 16 are united in any suitable manner so as to bind the flashing plies in place between the sections. One method of 60 binding the parts together is to, in effect, cement the same together by means of coatings of asphalt or other suitable adhesive material such as tar, asphaltic composition, or the like.

The top and bottom sections 15 and 16 of the wall member 10 may, if desired, be made of the same kind of material; for instance, an asphalt composition or other suitable impervious material.

The structure may be lightened in weight by incorporating in the body sections 15 and 16 suitable quantities of sawdust or other light weight filler material, it being observed, however, that it is desirable to avoid 75 an excessive quantity of such filler so that the impervious character of the wall member will not be adversely affected. Also, if desired, the top section 15 may be made of suitable impervious material, while the bottom section 16 is made of considerably lighter weight material, not necessarily impervious.

In Fig. 2, I have indicated a wall structure 18 formed of conventional brick work 85 and a roof 19 supported by suitable beams 20. As clearly shown in Fig. 2, the thickness and width of the wall part 10 of my improved roof joining unit are substantially the same as the corresponding dimensions of the bricks 90 of which the wall is formed. When the wall 18 is being built, the workman, when the wall reaches the proper height, spreads the usual layer of mortar and then, instead of bricks, places the wall block part of my improved roof joining structure in the wall substantially in the same manner in which bricks are 95 incorporated. The wall is built over the roof joining element just as though bricks had been placed in the wall. Thus, it appears 100

that there is no material departure in the manner of constructing the wall when incorporating my improved roof joining element. If desired to more securely anchor the wall member, suitable ties may be extended from the wall member to adjacent parts of the wall in a manner quite similar to the manner in which stone facing or the like is often tied to a wall structure.

10 To facilitate handling of the roof joining unit, I prefer to roll, fold or otherwise bundle the free or exposed portion of the flashing strips adjacent the outside surface of the wall block. This may be done by rolling the 15 free part of the flashing strip as indicated in Fig. 4, and the rolled or otherwise bundled strip may be temporarily maintained in such condition by suitable means such as one or more clips 21. The clips 21 may be in the 20 form of staples to embrace the rolled part of the flashing, the legs of the staples being driven in the top and bottom sections of the body member. As shown in Fig. 4, the clip 21 is in the form of a hook member having its 25 long leg driven in the lower section 16 of the wall block, and its upper leg terminating short of the top member 15. In this instance, the hook member is of bendable metal which permits the hook to be opened up merely by 30 bending the same outwardly and downwardly whereby the bundled flashing strip is released. Obviously, the holding means may be either merely bent downwardly and left substantially flat against the wall, or it may 35 be completely removed from the block member if desired.

In the present instance, I have shown the body member 10 as being divided in a plane extending at an angle to the top and bottom 40 faces of the wall block. By so disposing the line of separation, I avoid to some extent a sharp bend in the flashing strip at the point where it enters the wall block. This arrangement also is desirable in that the embedded 45 portion 17 of the flashing strips are held at a water shedding angle so that water which might accidentally find its way between the upper and lower sections is not apt to work its way across the entire width of the embedded portion to the interior of the wall.

50 For facilitating the formation of lapped joints between the ends of adjacent roof joining units, I provide an offset end arrangement as shown in Figs. 1 and 3. An end portion of the top section 15 of the wall member and a similar end portion of the bottom section 16 at the opposite end of the wall member is cut away as indicated at 22 and 23 respectively. The flashing strip, however, and its embedded marginal portion extends longitudinally of the wall member the full length of the combined top and bottom sections 15 and 16 as clearly shown. By reference to Fig. 3, it will be seen that the top

section 15 of the wall block at one end overlaps the projecting end of the bottom section 16 of the adjacent end of an adjacent roof joining unit. Also, that the adjacent portions of the flashing 11—11 overlap in a similar manner. The overlapped portions of the flashing are indicated at 24 in Fig. 3 and it will be understood that these overlapped portions are treated with tar or other roofing material in a well known manner to prevent leakage at the joints.

As clearly shown in Fig. 2, the flashing 11 overlaps roofing material layers 25 and 26, the latter having marginal portions turned upwardly against the face of the wall as indicated at 27, while the flashing 11 is disposed over the upturned marginal portions 27 and over the adjacent portions of the roofing plies so that the roofing material, in the corners around the roof where the latter joins the wall, is materially reinforced. The various overlapped elements and joints will, of course, be cemented together with roofing material in accordance with well-known practice to prevent leakage between the joints and a protective covering may be applied in the customary manner.

90 The flashing strips 12 and 13 may be made of any suitable impervious sheet material; for instance, tar paper or the like, but I prefer to make the flashings of suitable fabric such as canvas, which is impregnated with water-proofing material. Such canvas flashings are not apt to break or crack when the same are bundled to the condition shown in Fig. 4, and they are capable of withstanding such abuse as they might be subjected to during transportation and during the building of the wall in which they are incorporated.

95 I am aware that changes may be made in the above described structure without departing from the spirit of my invention, the scope of which should be determined by reference to the following claims, the same being construed as broadly as possible consistent with the state of the art.

100 I claim as my invention:

1. A unitary roof joining structure comprising a wall member and a flashing having a marginal portion embedded in said wall member, the free or exposed portion of said flashing being bundled adjacent one side of said wall member, and means for temporarily maintaining said flashing in bundled condition to facilitate handling of said unit.

115 2. A roof joining structure fabricated into a unit before installation thereof in a building structure, comprising a wall block and a flashing having a marginal portion secured to said block, said flashing extending longitudinally of the block and having one end substantially coincident with one end of the block and the other end extending beyond the other end of the block for facilitating the

- formation of a lapped joint with the flashing of another, similar roof joining unit.
3. A unitary roof joining structure comprising a wall member and a flashing having a marginal portion embedded in said wall member intermediate its thickness, a portion of said wall member above said embedded marginal flashing portion at one end, and a similar end portion of the wall member below said embedded marginal flashing portion at the other end of the structure, being cut away to facilitate the formation of lapped joints between the structure and similar juxtaposed structures.
4. In a roof joining, the combination of a wall block including top and bottom members, and a flashing strip having a marginal portion disposed between said top and bottom members, the latter being united so as to form, with said flashing, a unitary structure, the block part of which is adapted to be incorporated in a building wall structure when the latter is being built, a portion of the top member of said wall block at one end thereof and a similar portion of the bottom member at the other end of the wall block being cut away to facilitate the formation of lapped joints between the flashing strip of the structure and the flashing strips of similar juxtaposed structures.
5. A roof joining structure adapted to be fabricated into a unitary structure in a factory and subsequently incorporated in a building structure, comprising a wall member and a flashing having a portion secured to said member, the free or exposed portion of said flashing being bundled adjacent one side of said wall member to facilitate handling and installation of the wall member in a building wall when the latter is being built, said bundled flashing being adapted to be subsequently spread out to operative position.
6. A roof joining structure adapted to be fabricated into a unitary structure in a factory and subsequently incorporated in a building structure, comprising a wall member and a flashing having a marginal portion embedded in said member so as to provide a substantially impervious joint between said flashing and wall member, the free or exposed portion of said flashing being bundled adjacent one side of said wall member to facilitate handling and installation of the wall member in a building wall when the latter is being built, said bundled flashing being adapted to be subsequently spread out to operative position.
7. As an article of manufacture, a pre-formed roof joining device including a wall member and a flashing having a marginal edge attached to said wall member, the free portion of said flashing being bundled adjacent said wall member, and means to retain said flashing in a bundled condition.
8. As an article of manufacture, a pre-formed roof joining device including a wall member and a flashing attached to said wall member, said flashing being bundled adjacent said wall member.
